UNITED STATES PATENT OFFICE.

MATHEW ALSTON, OF HAMILTON, ILLINOIS.

CURRYCOMB.

SPECIFICATION forming part of Letters Patent No. 679,933, dated August 6, 1901.

Application filed February 25, 1901. Serial No. 43,806. (No model.)

To all whom it may concern:

Be it known that I, MATHEW ALSTON, a citizen of the United States, residing at Hamilton, in the county of Hancock and State of Illinois, have invented certain new and useful Improvements in Currycombs; and I do hereby declare the following to be a full, clear, and exact description of the invention, such as will enable others skilled in the art to which it appertains to make and use the same.

This invention relates to currycombs; and it has for one object to provide in connection with an ordinary currycomb an attachment constructed and arranged to efficiently clean over the legs and the bony parts of the animal without injury, further objects and advantages of the invention being evident from the following description.

In the drawings forming a portion of this specification, and in which like numerals of reference indicate similar parts in the several views, Figure 1 is a perspective view showing one embodiment of the invention. Fig. 2 is a perspective view showing a spring-back style of comb attachment. Fig. 3 is a section on line 3 3 of Fig. 2. Fig. 4 shows a corrugated form of cleaning-plate. Fig. 5 shows a further modification of cleaning-plate.

Referring now to the drawings, and more particularly to Fig. 1, 5 represents the back of the currycomb, which is in the form of a flat rectangular plate having the tooth-bars 6 attached to its under side and disposed parallel, as is usual. As the ordinary teeth of a comb are such as to give pain to a horse when used upon the legs and over bony portions, I have provided an attachment for use in cleaning such tender portions of the horse.

The attachment in question consists of a plate 6', which is bent into a curve and from one face of which project studs 7, formed by striking up the metal of which the plate is formed. The outer edge of the upper concaved face of the plate is riveted to the rear portion of the plate 5, while the outer edge of the convex portion is bent under, as shown at 8, and is riveted to the forward portion of the plate, the studs projecting upwardly or away from plate 5. The plate 6' extends through-

out the length of plate 5 and its width may vary as desired.

The plate 3 has the usual handle 10, and it will be noted that as the studs are rounded at their ends this plate may be rubbed over the anatomy of a horse without pain to him, and at the same time the plate is sufficiently rough to have an efficient action.

In the construction shown in Fig. 2 of the drawings the yoke-plate 11 of the handle 12, 60 and which is attached to the back plate 13 of the comb, has its extremities directed forwardly, and these extremities are spaced upwardly from the plate, and the rear edge of the studded plate 14, corresponding to the 65 plate 6', is disposed loosely beneath these ends of the yoke-plate, so that this rear edge may have movement toward and away from plate 5 and the plate may be yieldable.

Instead of the studs 7 a plate may be used, 70 as shown in Fig. 4, which is corrugated longitudinally, or a plate may be used, such as shown in Fig. 5, having elongated studs. In each case, however, the plate must be roughened, but without the formation of sharp 75 edges, such as have the teeth of the comb.

In practice other modifications of the invention may be made and any suitable materials and proportions may be used for the various parts without departing from the 80 spirit of the invention.

What is claimed is—

1. The combination with a currycomb having teeth on one face of a curved plate secured to the opposite face of the comb and 85 having projections struck up therefrom without breaking the metal of which the plate is formed.

2. The combination with a currycomb having teeth on one face, of a curved, spring- 90 metal plate attached to the opposite face of the comb at one edge and having its opposite edge free to move toward and away from the comb, said plate having projections struck up therefrom without breaking the metal of 95 which the plate is formed.

3. The combination with a currycomb comprising a plate having teeth at one side, of a handle including a yoke-plate attached to the first-named plate with its extremities spaced 100

upwardly therefrom, and a metal, curved plate attached at one edge to the first-named plate and having its opposite edge disposed between said plate and the spaced ends of
5 the yoke-plate for movement therebetween, said curved plate having projections struck up therefrom.

In testimony whereof I hereunto sign my name, in the presence of two subscribing witnesses, on the 11th day of February, 1901. 10

MATHEW ALSTON.
